METHOD OF AND MEANS FOR PROCESSING
MULTIPLE FILAMENT THREAD BUNDLESLouis E. Lovett, Cleveland Heights, Ohio, assignor
to Industrial Rayon Corporation, Cleveland,
Ohio, a corporation of Delaware

Application June 20, 1938, Serial No. 214,764

6 Claims. (Cl. 18-8)

This invention pertains to a novel method of and means for manufacturing thread-like articles characterized by a large number of filaments. While the method and apparatus of the invention may be advantageously employed in the manufacture of multiple filament thread such as that customarily used in knitting or weaving operations, the practice of the invention is especially adapted to the continuous processing of thread bundles of the relatively large titer ordinarily employed in the manufacture of staple fiber; e. g., 5,000 to 100,000 denier. As hereinafter used, the term "thread" will be employed in a generic sense to cover thread bundles of this type, multiple filament thread of the kind customarily employed in knitting and weaving operations, and thread-like articles generally, whether of natural or synthetic origin.

Among other things, the invention contemplates the substantially tensionless treating of thread on a series of thread-advancing thread store devices. In the processing of thread upon most, if not all, types of thread-advancing thread store devices, tensional stresses are induced in the thread. The introduction of such tensional stresses, especially in multiple filament thread, tends to damage the thread by weakening and breaking the individual filaments, which often become snarled and knotted to such an extent as to make it very difficult to process the thread upon the thread-advancing thread store devices.

One of the advantages of the present invention is that these stresses can be minimized by the practice of the invention, thereby eliminating the resultant breaking and weakening of the filaments. A further important advantage follows from the fact that the invention provides an opportunity to treat the thread more thoroughly. Thus the physical immersion of the thread in the processing liquid permits each of the filaments comprising the thread to be completely surrounded by the treating bath. Other advantages will be apparent as the description of the invention proceeds.

The method and apparatus of the invention may find application in any mode of producing or processing thread, particularly multiple filament thread of relatively large titer. The novel method and means of the invention may, for example, readily be adapted to any of the known processes for manufacturing artificial silk or wool thread; e. g., the viscose, cuprammonium, cellulose acetate and casein processes. Although any type of thread may be advantageously manufactured or processed according to the methods suggested by

the instant invention, for purposes of illustration the invention will be described and illustrated as applied to the continuous process of manufacturing a viscose artificial silk thread bundle suitable for reduction by cutting or otherwise to fibers of staple length.

In the accompanying drawings, which illustrate but one of the possible embodiments of the invention, Figure 1 represents a front elevation of a continuous processing machine in which the method and means of the invention are employed. Figure 2 is a plan of the machine of Figure 1. Figure 3 is a partial front elevation of a portion of the machine from line 3-3 of Figure 2. Figure 4 is a sectional elevation along line 4-4 of Figure 3. Figure 5 is a sectional elevation of a thread-advancing thread store device which may be used to advantage in the machine of Figures 1 and 2. Throughout the drawings, corresponding parts bear corresponding reference characters.

In Figures 1 and 2 of the drawings, the machine is shown as embodying a plurality of thread-advancing thread store devices disposed in horizontal arrangement, each of said devices being supported and driven from one end only thereof. As will appear from consideration of the principles of the invention as hereinafter set forth, any one of various other arrangements of thread-advancing thread store devices may, if desired, be substituted for that shown. Neither is it necessary to the practice of the invention that the thread-advancing thread store devices take the form of thread-advancing reels, as illustrated; but for convenience in describing the invention the thread-advancing thread store devices will be referred to hereinafter simply as reels.

Generally speaking, the apparatus comprises a plurality of such reels from one to another of which the thread, preferably in the form of a slack loop, proceeds through a processing bath. The slack loop may conveniently be formed in the course of the threading-up operation by permitting a sufficient length of thread to be discharged from the unsupported end of one of a pair of reels devoted to the same or different processing stages, permitting said thread to hang loosely in the processing medium through which it is to be passed, and conducting the leading end of the thread to the supported end of the other reel of said pair. In this manner the thread will be continuously discharged from the first of said reels; advanced through the proc-

essing medium in the form of a slack loop, and withdrawn by the succeeding reel.

The apparatus illustrated in Figures 1 and 2 embodies two identical operating faces extending lengthwise thereof each of which comprises at least one but may comprise two, three or more similarly arranged tiers of reels. Each tier has associated therewith a trough 8 containing a coagulating bath 7 in which are immersed a plurality of spinnerets 9 by means of which are formed the multiple filament threads A. The latter are combined by any suitable means such as the guide 10 to form thread bundle B which is passed in sequence to each of the reels of the tier, passing thence to a cutter or the like for reducing the thread bundle to fibers of staple length.

Although the reels may take any suitable form, reels of the type illustrated in Figures 3, 4 and 5 of the accompanying drawings may be employed to advantage. The reels shown are similar in design and operation to that shown, described and claimed in Knebusch Patent 2,210,914 and therefore need be only briefly explained herein. From the reel described in said patent they differ principally in that they are of cantilever form, as a result of which the thread may be discharged from the unsupported end thereof.

The reel preferably comprises two rigid reel members 11 and 12 made up of a plurality of longitudinally extending bar members 13 and 14, respectively, which bar members are alternately disposed with respect to each other to form the generally cylindrical periphery of said reel. The reel member 11, which is referred to as the concentric member, consists of a supporting spider 15 which supports the bar members 13 thereof and is secured to drive shaft 16 by set screw 17 so as to rotate therewith. The second reel member 12, known as the eccentric member, is provided with a supporting disc 18 mounted in such a manner as to rotate freely upon the frame member 19 in which the shaft 16 is journaled. The bearings for the reel members are so arranged that the axes thereof are in offset and inclined relation to each other.

By reason of the above-described arrangement, when the shaft 16 is rotated, the reel member 11 mounted concentrically upon and fixed thereto likewise rotates and because of the interdigitating relation of the bars 13 and 14 drives reel member 12 by bar-to-bar contact. At the same time, the relative radial displacement of the bars causes the thread to be supported first by one set of bars and then by the other while the inclined relation causes it to advance longitudinally of the reel as a whole. Taken together, both actions result in progressing the thread from one end of the reel to the other substantially in the form of a helix made up of a large number of closely spaced turns.

Referring again to Figures 1 and 2, the thread bundle B, after passing through the guide 10, is caused to wind on the first reel 21, which serves as a holding reel for permitting the regeneration of the cellulose content of the viscose to proceed to substantial completion. Although a suitable coagulating liquid may, if desired, be showered upon the thread bundle B on reel 21, it has been found that no additional coagulating liquid need be supplied to the thread bundle on this reel, sufficient liquid being carried over from the coagulating bath for this purpose. Tray 26, an extension of trough 8, may be employed to catch

the liquid dripping from reel 21 and direct it back to said trough.

Thread bundle B may be subjected on the reels 22a, 22b, etc. to any of a variety of suitable processing treatments such as washing, desulphurizing, bleaching, etc.

Due to the large size of the thread bundle B, it is desirable to employ methods of processing which will relieve tensional stresses induced in the individual filaments thereof as well as to insure complete and thorough processing. This may be done in any suitable manner but may be accomplished to advantage by employing two reels such for example, as reels 22a and 22b for a single processing stage, winding the thread bundle B first upon said reel 22a. Between reels 22a and 22b the thread bundle B is permitted to form a slack loop B' extending from the discharge point C on reel 22a to the lead-on point D on reel 22b. A single processing liquid is applied to the thread bundle B upon both reels from distributors 27 supplied from storage tanks 28 by conduits 29, being caught in the troughs 30 disposed therebelow.

This loop B' is suspended in the liquid 31 contained in an arcuate reservoir 32 toward which troughs 30 may slope, if desired. Supply pipe 33 and overflow pipe 34 serve to keep a constant quantity of fresh processing liquid in reservoir 32. The overflow pipe 34 is connected to a suitable conduit (not shown) which conducts excess processing liquid either to the sewer, in the event that the processing liquid is to be used only once, or, if the processing liquid is of such nature that it may be re-used, to make-up means to be pumped back to storage tanks 28 for recirculation.

In the case of reels 22a and 22b, the thread bundle B discharged from the unsupported end of reel 21 proceeds to the supported end of reel 22a which is rotated in a counterclockwise direction. It is advanced longitudinally along the periphery of reel 22a toward the unsupported end thereof in generally helical form. Upon reaching the unsupported end of reel 22a, thread bundle B proceeds through reservoir 32 in the form of slack loop B' until it reaches the supported end of reel 22b likewise rotated in counterclockwise direction. Upon reel 22b it is again advanced toward the unsupported end thereof in generally helical form. As will be observed from Figures 1 and 2 of the drawings, the reels 22a and 22b are disposed obliquely to the longitudinal axis of the apparatus as a whole, so that the discharge end of reel 22a is in apposition to the receiving end of reel 22b.

After thread bundle B has been subjected to the desired treatment on reels 22a and 22b, it is passed through an aperture 42 in the wall of the trough 30 to and between a pair of squeeze rolls 37 provided for the purpose of removing as much as possible of the processing liquid carried over from the stage through which the thread bundle has just passed.

A bracket 43 secured to the wall of trough 30 serves to support squeeze rolls 37. The lower roll is mounted on the rotatable shaft 40, while the upper roll is mounted on a short shaft 44 movable in a vertical plane to permit adjustment of the space between the rolls, such adjustment being effected through screws 45 by compressing or releasing springs 46 held against the bearing blocks 47 at either end of shaft 44. A short channel 48 disposed below the squeeze rolls 37 carries the liquid removed from the thread

bundle by said squeeze rolls through the aperture 42 into the trough 39. Squeeze rolls 37 may be positively driven from a shaft 38 extending lengthwise of the machine by means of bevel gears 39, shaft 40 and spur gears 41. The squeeze rolls 37 serve to prevent contamination of the processing liquid of subsequent processing stages.

As many processing stages as desired may be included in the apparatus, taking into account the particular process of production being followed. Each subsequent processing stage to which the filament bundle B is conducted will follow in order, utilizing in each case a pair of reels similar to reels 22a and 22b. Appropriate processing steps following the holding stage on the reel 21 may include a washing stage, desulphurizing, a second washing stage, bleaching, a final washing stage, oiling, etc., after which the thread bundle may be reduced to fibers of staple length. Alternatively, after the final washing the thread bundle may be conducted to a drying reel, dried, and collected in suitable package form.

In the illustrated embodiment of the invention the individual reels are driven in a counterclockwise direction in order to obtain the greatest length of thread in the loop B' consistent with the floor space which may be allotted to the apparatus. The reels may be driven from a power source (not shown) by a longitudinal shaft 50 and gear boxes 51 supported from a central frame, as indicated, on which the reel frame members may be mounted. The shaft 38 actuating the squeeze rolls 37 may be driven from the same source of power as the shaft 50. The counterclockwise rotation of the reels necessitates the provision of apertures 42 in the sides of the troughs surrounding reels 21, 22a, 22b, etc., to permit the passage of the thread bundle from one processing stage to another.

Various modifications of the apparatus shown and described may be made without in any way affecting or departing from the scope or spirit of the invention. It may be found, for example, that in some instances the introduction of the processing liquid from distributor 27 on the second reel in each processing stage is unnecessary, the application of the processing liquid on the first reel being sufficient, in view of the subsequent immersion of the loop, to effect the thorough processing of the thread bundle. If it is desired to increase the period of processing, it is a simple matter to provide additional reels for each processing stage or for any given stage or stages where additional treatment may be required.

The practice of the instant invention provides a very efficient method of processing thread of large denier. As previously indicated, the description of the invention in its application to the production of artificial silk thread for conversion into fibers of staple length is not intended as a limitation, since it is equally well adapted to the production of any other kind of thread, artificial straw, artificial horsehair or similar thread-like articles. It is intended that the patent shall cover, by suitable expression in the appended claims, whatever features of patentable novelty reside in the invention.

What is claimed is:

1. The method of applying a processing liquid to a multiple filament thread bundle which is traveling from one point to another in extended condition comprising impressing the characteristics of an advancing helix upon said thread bundle at each of two laterally spaced zones along its path of travel; advancing said helices at the same peripheral speed; and, in the intermediate zone through which said thread bundle travels from one to the other of said helices, causing said thread bundle to proceed through a body of processing liquid in the form of a substantially tensionless slack loop.

2. The method of applying a processing liquid to a multiple filament thread bundle which is traveling from one point to another in extended condition comprising continuously but temporarily storing said thread bundle upon a thread-advancing reel at each of two laterally spaced zones along its path of travel; rotating said thread-advancing reels at the same peripheral speed; and, in the intermediate zone through which said thread bundle travels from one to the other of said thread-advancing reels, causing said thread bundle to proceed through a body of processing liquid in the form of a substantially tensionless slack loop.

3. The method according to claim 2 in which said multiple filament thread bundle is subjected to additional processing treatment on one or both of said thread-advancing reels.

4. The method according to claim 2 in which substantially all of the adherent processing liquid is expressed from said multiple filament thread bundle after leaving the second of said thread-advancing reels.

5. Apparatus for the application of one or more processing liquids to a multiple filament thread bundle which is traveling from one point to another in extended condition comprising a reservoir; means for maintaining a supply of processing liquid in said reservoir; and at least two independently functioning thread-advancing thread store devices operating at substantially the same peripheral speed disposed in such relation to said reservoir that a thread bundle passing from one to the other of said devices will be immersed in the form of a slack loop in the processing liquid in said reservoir, said slack loop taking the form of a catenary curve.

6. Apparatus for the application of one or more processing liquids to a multiple filament thread bundle which is traveling from one point to another in extended condition comprising a reservoir; means for maintaining a supply of processing liquid in said reservoir; at least two independently functioning thread-advancing thread store devices operating at substantially the same peripheral speed disposed in such relation to said reservoir that a thread bundle passing from one to another of said devices will be immersed in the form of a slack loop in the processing liquid in said reservoir, said slack loop taking the form of a catenary curve; and means adjacent the last of said thread-advancing thread store devices for removing substantially all of the adherent processing liquid from said thread bundle.

LOUIS E. LOVETT.
